DESIGN FOR A HEATING STOVE

Lee S. Chadwick, Shaker Heights, and John
Alger Dahlstrom, Bay Village, Ohio, assignors
to Perfection Stove Company, Cleveland, Ohio,
a corporation of Ohio

Application July 24, 1936, Serial No. 64,033

Term of patent 14 years

To all whom it may concern:

Be it known that we, (1) Lee S. Chadwick and
(2) John Alger Dahlstrom, citizens of the United
States, residing at (1) Shaker Heights, (2) Bay
Village, in the county of Cuyahoga, and State of
Ohio, have invented a new, original, and ornamental
Design for Heating Stoves, of which the
following is a specification, reference being had
to the accompanying drawing forming part here-

of, and wherein Fig. 1 is a front elevation of a
heating stove showing our new design; Fig. 2 is
a right hand side elevation thereof, and Fig. 3
is a plan view.

We claim:

The ornamental design for a heating stove as
shown.

LEE S. CHADWICK.
JOHN ALGER DAHLSTROM.
